UNITED STATES PATENT OFFICE.

WILLIAM FRERICKS, OF STEAMBOAT ROCK, IOWA.

FILLER DEVICE FOR EGG CASES OR CRATES.

Application filed March 25, 1924. Serial No. 701,777.

To all whom it may concern:

Be it known that I, WILLIAM FRERICKS, a citizen of the United States, residing at Steamboat Rock, in the county of Hardin and State of Iowa, have invented certain new and useful Improvements in Filler Devices for Egg Cases or Crates, of which the following is a specification, reference being had therein to the accompanying drawings.

10 This invention relates to a filler device for an egg case or crate, and the object of the invention is the construction of a simple and efficient filler device, formed from rubber material, and which will be hard to

15 separate when assembled.

Another object of the invention is the construction of the interlocking sections, which are provided with efficient interlocking features as hereinafter specifically described.

20 With the foregoing and other objects in view, my invention comprises certain novel combinations, constructions and arrangements of parts as will be hereinafter described, illustrated in the accompanying drawings, and more particularly pointed out in the appended claims.

In the drawings:

Figure 1 is a top plan view of a filler device constructed in accordance with the 30 present invention, while

Figure 2 is a side view of the same.

Figure 3 is a section, taken on line 3—3, Fig. 1, and looking in the direction of the arrows.

35 Figure 4 is a fragmentary view, in side elevation, of one of the surrounding sections.

Figure 5 is a sectional view, taken on line 5—5, Fig. 4 and looking in the direction of the arrows.

40 Figure 6 is a sectional view of one of the inner interlocking sections.

Referring to the drawings by numerals, 1 designates the surrounding sections of my device, while 2 are the interlocking sections. I preferably form the device so that it may hold thirty-six eggs in a crate or case. It will be obvious that as many of these devices may be employed as the operator desires, and I preferably form the sections of the device from strips of rubber or other suitable yielding material, so as to increase the efficiency of the device in preventing the eggs from being broken during handling or shipment.

55 Each surrounding section is provided with

a plurality of elongated openings 3, and at the upper and lower ends of the openings 3 are formed sets of V-shaped notches 4 for the purpose hereinafter described. 60

Each interlacing section 2 is provided with vertically aligned sets of cutout portions 5. Each cutout portion 5 is provided with a pair of flat bevelled edges 6, that allow the interlacing section 2 to more readily pass through the opening 3 of section 1, and these flat bevelled edges 6 merge at their inner ends in a double V-shaped notch 7, which notch 7 fits into the V-shaped notches 4 on the surrounding section, as 70 shown in Figs. 1, 2 and 3, thereby increasing the interlocking action of the sections, whereby a more stable and efficient filling device is produced.

By reason of the sections being formed 75 preferably of rubber, the interlacing sections can be threaded or laced through the elongated openings 3 of the surrounding sections and the notched portions readily accommodate themselves to each other, whereby the 80 assembling of the device is easily accomplished.

It is a known fact that rubber affords a very yielding surface and as I preferably 85 form my filler device of rubber material the percentage of eggs broken in handling or in transit is reduced to a minimum where my device is used.

While I have described the preferred embodiment of my invention, and have illustrated the same in the accompanying drawings, certain minor changes or alterations 90 may appear to one skilled in the art to which this invention relates, during the extensive manufacture of the same and I, therefore, 95 reserve the right to make such alterations or changes as shall fairly fall within the scope of the appended claims.

What I claim is:

1. A filler of the character described comprising strips extending parallel to each other and provided with transversely extending slots substantially rectangular in shape and having V-shaped notches at the ends of the slots providing inwardly converging faces, and a second set of strips extending transversely to the first strips and through the slots formed therein, the strips of the second set being each provided with V-shaped notches leading from opposite side 105 edges in opposed relation to each other and providing reduced portions adapted to be 110

positioned in the slots of the first mentioned strips, the second mentioned strips being bevelled along the edges of the V-shaped notches to provide converging faces fitting 5 into the V-shaped notches of the first mentioned strips and contacting with the converging faces thereof.

2. The structure of claim 1 having the strips formed of yieldable material to provide 10 a binding engagement between the con-

tacting bevelled face thereof, the walls of the V-shaped notches leading from the sides of the second set of strips having their outer end portions flared outwardly to permit the strips of the second set to be readily passed 15 through the slots in the strips of the first set.

In testimony whereof I hereunto affix my signature.

WILLIAM FRERICKS
